COLANDER OR THE LIKE

Everett M. Millard, North Hollywood, Calif.

Application February 10, 1951, Serial No. 14,174

Term of patent 14 years

(Cl. D44—10)

To all whom it may concern:

Be it known that I, Everett M. Millard, a citizen of the United States of America, whose post office address is Post Office Box 589, in the city of North Hollywood, county of Los Angeles, State of California, have invented a new, original, and ornamental Design for a Colander or the like, of which the following is a specification, reference being had to the accompanying drawing, forming a part hereof.

Figure 1 is a top perspective view of a collapsible colander showing my new design, the device being shown open;

Figure 2 is a side elevational view of the device of Figure 1;

Figure 3 is a bottom plan view thereof shown closed; and

Figure 4 is a perspective view of one leaf of the device, removed therefrom.

I claim:

The ornamental design for a colander or the like, as shown and described.

EVERETT M. MILLARD.
